UNITED STATES PATENT OFFICE.

JOHN J. GUIDER, OF NORTH PELHAM, NEW YORK.

SLIDING DRAPERY HOLDER.

Application filed May 17, 1923. Serial No. 561,679.

To all whom it may concern:

Be it known that I, JOHN J. GUIDER, a citizen of the United States, residing in North Pelham, in the county of Westchester and State of New York, have invented certain new and useful Improvements in Sliding Drapery Holders, of which the following is a specification.

The present invention relates to drapery or curtain supporting devices in which a supporting pole or curtain pole having rings therearound and slidable thereon is used, and one object of the invention is to provide a device of this character by which the supporting pole and rings are concealed from view by one side of the drapery or curtain.

Another object is to provide a device of this character by which the upper edge of the drapery or curtain is sustained in position above the pole and rings for filling in a gap-space, the pole and rings being concealed from view by one side of the drapery or curtain.

Another object is to provide a device of this character by which the drapery or curtain is maintained in supported relation with a pole and ring by the weight of the drapery or curtain upon a portion of the ring removably connecting the drapery or curtain to the ring.

Another object is to provide a device of this character in which the drapery or curtain is provided with means with which means on a pole supported ring is engageable for removably connecting the ring to the drapery or curtain, the means on the ring being maintained in operative relation to the means on the drapery or curtain by the weight of the drapery or curtain, and being disconnectable from the means on the drapery or curtain when the weight of the drapery or curtain is relieved, the drapery or curtain being thereby removable from the ring and pole.

I accomplish these and such other objects as may appear during the following description, by way of example, of one of the possible embodiments of the invention shown by the accompanying drawings in which Figure 1, is a side elevation of a ring and a ferrule plate for cooperating therewith.

Figure 2, is a front elevation of the ring and ferrule plate.

Figure 3, is a side elevation, on a larger scale than Figs. 1 and 2, of the ring and ferrule plate, the ring being disconnected

from the ferrule plate but in position for connection thereto.

Figure 4, is a front elevation, on the same scale as Fig. 3, of the ring and ferrule plate, the ring being disconnected from the ferrule plate but in position for connection thereto.

Figure 5, is a rear view of the drapery or curtain showing a supporting pole or curtain pole, a plurality of rings therearound, a plurality of ferrule plates secured to the drapery or curtain, and a draw cord for sliding the rings along on the pole.

Figure 6, is a view of Fig. 5 looking in the direction of the arrow, and

Figure 7, is a front elevation, on an enlarged scale, of the ring.

Similar reference characters denote similar parts throughout the several views.

Referring to Fig. 1, the ring 10 carries at one side the up-standing portion 11 which extends somewhat above the top of the ring, the up-standing portion 11 being attached to the ring 10 at its lower end and spaced somewhat from the adjacent side of the ring, the intention being that the up-standing portion 11 shall be engageable in the ferrules 12 of the ferrule plate 13 later described, these ferrules being received edgewise in the space between the up-standing portion 11 and the adjacent side of the ring 10, the lower ferrule 12 resting upon the means for attaching the upstanding portion to the ring, the up-standing portion 11 being slidably engageable in the ferrules 12 and preferably with a rather snug fit. The ring 10 is provided at its bottom with a depression or recess 14 for the purpose later stated.

The up-standing portion 11 may be integral with the ring 10, the up-standing portion and ring being formed from a suitable wire or metal rod one end of which provides the up-standing portion 11, the wire or rod at the lower end of the up-standing portion being bent into an eye 15, Fig. 3, and being extended and carried upward and over and around in ring form and provided at the end of its extension with an eye 16 arranged at right angles to the eye 15 and hooked therein, the up-standing portion 11 being spaced away from the adjacent side of the ring by the turn of the eye 15, and the depression or recess 14 being formed by bending the wire or rod.

The ferrule plate 13 is of suitable metal, the ferrules 12 being up-struck from one surface thereof, or integral therewith, and

spaced apart; or the ferrules 12 may be secured in any suitable manner, not shown, but readily understood, to the ferrule plate.

The ferrule plate 13 preferably is substantially oblong in shape, and is provided near its edges with holes 17 whereby it may be attached by sewing or other suitable means to the drapery or curtain.

In operation the ferrule plates 13 are attached to the drapery or curtain near the top thereof, the rings 10 being around the pole P. The up-standing portion 11 of each ring 10 is slidably inserted in the ferrules 12 of each ferrule plate from the under side of the ferrules, the ferrules passing over the up-standing portion 11 and between it and the adjacent side of the ring, the lowermost ferrule resting upon the eye 16 of the ring, the up-standing portion or pin 11 being maintained in engagement with the ferrules by downward pressure or pull on the ferrules due to the weight of the drapery or curtain.

By lifting the drapery or curtain to relieve the pressure or pull of this weight from the ferrules the up-standing portion 11 may be withdrawn from the ferrules and the drapery or curtain removed from the ring and pole.

By referring to Fig. 5, it will be noted that a plurality of ferrule plates 13 is attached in alinement to the drapery near its top and tend to stiffen the drapery, thereby due to the stiffening of the drapery by the series of ferrule plates providing a transverse zone of rigidity for the drapery adjacent to and above the series of ferrule plates, whereby the drapery above the line of the ferrule plates, and above the supporting pole, is caused to stand substantially upright for filling in a gap space.

For drawing the drapery or curtain towards a desired end of the pole P a suitable draw cord 18 may be attached to each ring 10 by means of the depression or recess 14.

Having thus described my invention, it should be understood that there may be modifications thereof and variations therein without departing from the spirit of the invention or exceeding the scope of the appended claims.

What I claim and desire to protect by Letters Patent is:—

1. In a drapery supporting device, a supporting pole; a plate secured to one side of the drapery having alined ferrules thereon; a ring around the pole having an up-standing portion fixedly secured to one side thereof and spaced from the adjacent side of the ring; the up-standing portion being removably insertable in said ferrules from the under side of the ferrules, the ferrules passing over said portion and between it and the adjacent side of the ring, the up-standing

portion being maintained in position in the ferrules by downward pull on the ferrules due to the weight of the drapery.

2. In a drapery supporting device, a supporting pole; a plate secured to one side of the drapery having alined ferrules thereon; a ring member around the pole comprising a ring portion and an up-standing portion fixedly secured to one side thereof, the up-standing portion having an eye at its lower end connecting the up-standing portion and ring portion and spacing them apart; the ring portion having an eye hooked in the first mentioned eye; the up-standing portion being removably insertable in said ferrules from the under side of the ferrules, the ferrules passing over said portion and between it and the adjacent side of the ring, the up-standing portion being maintained in position in the ferrules by engagement of the lowermost ferrule with the second mentioned eye and downward pull on the ferrules due to the weight of the drapery.

3. In a drapery supporting device, a supporting pole; a plate secured to one side of the drapery having alined ferrules thereon; a ring member around the pole comprising a ring portion and an up-standing portion fixedly secured to one side thereof, the up-standing portion having an eye at its lower end connecting the up-standing portion and ring portion and spacing them apart; the ring portion having an eye hooked in the first mentioned eye; the up-standing portion being removably engageable in said ferrules and maintained in engagement therein by the weight of the drapery; the up-standing portion being removably insertable in said ferrules from the under side of the ferrules, the ferrules passing over said portion and between it and the adjacent side of the ring, the up-standing portion being maintained in position in the ferrules by engagement of the lowermost ferrule with the second mentioned eye and downward pull on the ferrules due to the weight of the drapery.

4. In a drapery supporting device, a supporting pole; a plate secured to one side of the drapery having alined ferrules thereon; a ring member around the pole comprising a ring portion and an up-standing portion fixedly secured to one side thereof, the up-standing portion having an eye at its lower end connecting the up-standing portion and ring portion and spacing them apart; the ring portion having an eye hooked in the first mentioned eye and having means for securing a draw cord thereto; the up-standing portion being removably insertable in said ferrules from the under side of the ferrules, the ferrules passing over said portion and between it and the adjacent side of the ring, the up-standing portion being maintained in position in the ferrules by engagement of the lowermost ferrule with the sec-

ond mentioned eye and downward pull on the ferrules due to the weight of the drapery; said ring portion, up-standing portion, eyes and means for securing a draw cord thereto being formed integral by bending a piece of wire or metal rod.

5. In a drapery supporting device, a supporting pole; a plurality of plates secured to the drapery in alinement transversely of the drapery near its top, each plate having thereon alined ferrules; and a plurality of rings around the pole, a ring for each plate; each ring having an up-standing portion fixedly secured to one side thereof and spaced from the adjacent side of the ring; the up-standing portions of the rings being removably insertable in the ferrules of the plates from the under side of the ferrules and maintained in position in the ferrules by downward pull on the ferrules due to the weight of the drapery; the alined plates providing a zone of rigidity for the drapery at its top adjacent to and above the plates and supporting pole and causing the portion of the drapery above the plates and pole to stand substantially upright for filling in a gap space.

6. In a drapery supporting device, a supporting pole; a plurality of plates secured to

the drapery in alinement transversely of the 30 drapery near its top, each plate having thereon alined ferrules; a plurality of rings around the pole, a ring for each plate; each ring comprising a ring portion and an up-standing portion fixedly secured to one side 35 thereof; the up-standing portion having an eye at its lower end connecting the up-standing and ring portions and spacing them apart; the ring portion having an eye hooked in the first mentioned eye; the up-standing 40 portions of the rings being removably insertable in the ferrules of the plates from the under side of the ferrules and maintained in position in the ferrules by downward pull of the lowermost ferrules of the 45 plates on the second mentioned eyes of the rings due to the weight of the drapery; the alined plates providing a zone of rigidity 50 for the drapery at its top adjacent to and above the plates and supporting pole and causing the portion of the drapery above the plates and pole to stand substantially upright for filling in a gap space.
